UNITED STATES PATENT OFFICE

105,628

DESIGN FOR AN ELECTRIC ILLUMINATING FIXTURE

Paul J. Wiesler, St. Louis, Mo., assignor to Edwin
F. Guth Company, St. Louis, Mo., a corpora-
tion of Missouri

Application April 19, 1937, Serial No. 68,861

Term of patent 14 years

To all whom it may concern:

Be it known that I, Paul J. Wiesler, a citizen of the United States and a resident of St. Louis, Missouri, have invented a new, original, and ornamental Design for an Electric Illuminating Fixture, of which the following is a specification, reference being had to the accompanying drawing forming part thereof, in which

Fig. 1 is a side elevational view of an electric illuminating fixture showing my new design; and,

Fig. 2 is a bottom plan view of said fixture.

The stippling indicates light effects; the lighter stippling indicates relatively brighter areas.

I claim:

The ornamental design for an electric illuminating fixture, substantially as shown and described.

PAUL J. WIESLER.
